ATTORNEY

UNITED STATES PATENT OFFICE.

JEROME FOUNTAIN, OF OAKLAND, CALIFORNIA.

CAN OPENER AND CLOSURE.

1,061,602.

Specification of Letters Patent. Patented May 13, 1913.

Application filed September 25, 1912. Serial No. 722,271.

To all whom it may concern:

Be it known that I, JEROME FOUNTAIN, a citizen of the United States, residing at Oakland, in the county of Alameda and State of California, have invented a new and useful Can Opener and Closure, of which the following is a specification, in such full and clear terms as will enable those skilled in the art to construct and use the same.

This invention relates to a device for opening condensed milk cans, and its object is to provide an opener which can also be used for the purpose of sealing the openings produced until it is desired to again pour liquid from the can.

It will be understood that large quantities of condensed milk and other liquids are sold in cans, which cans are usually opened by punching two holes therein at opposite sides of the can. When the liquid is poured from the openings in the can it becomes smeared around the opening more or less and if allowed to stand around for any length of time, flies light upon it and thus poison the product.

With this invention a device is provided for covering up the openings to prevent flies from having access thereto and to prevent dirt from falling therein, thus keeping the product clean.

In the drawings in which the same numeral of reference is applied to the same portion throughout the several views, Figure 1 is a side elevation of a can having this opening device applied thereto, Fig. 2 is a plan view of the device attached to the can, Fig. 3 is a plan view of the device attached to the can and showing the two openings covered when the can is to be set away, and Fig. 4 is a side elevation of the opener.

The numeral 1 indicates the can, which may be of any desired size, to which the opener is applied. The opener comprises a spring 2 having a pointed punch 3 secured thereto above which is a small knob 4 to punch the punch 3 through the metal of the can. The spring 2 is pivotally secured to a

plate 5, which plate is provided with hooked ends 6 and 7 to secure the opener releasably to the can top. In order to remove the opener from the can top, the hooked end 7 is provided with an extension 8 to act as a handle. The plate 5 and spring 2 are both pivotally secured to a cover plate 9. This cover plate has openings 10 and 11 therein and has a portion of its edge bent down as shown at 12 and 13 to hold it centrally in place on the can top, and also to afford means whereby the cover may be rotated over the openings produced in the can. The manner of operating the device is indicated in Figs. 2 and 3.

It will be seen that the cover plate 9 is releasably attached to the can top by means of the bar 5 and holes are punched in the can adjacent the openings 10 and 11 of the cover plate. The punch is then removed from the holes in the can by the spring. When it is desired to set the can away for a time, the cover plate is rotated a small amount as indicated in Fig. 3, so that both of the openings produced in the can are completely covered, thus preventing dirt and flies from having access thereto. When it is desired to use the product in the can, the cover plate may be returned to the position indicated in Fig. 2 and if the product has gummed up the openings therein, it may be readily cleaned by inserting the punch 3 in each opening.

Having thus described my invention what I claim as new and desire to secure by Letters Patent of the United States, is as follows:

1. In a can opener and closure therefor, a cover plate having notches cut therein, means to secure the cover plate to a can, and a punch pivotally mounted upon said cover plate so that it may be moved to a position adjacent each of the notches in said cover plate, substantially as described.

2. In a can opener and closure therefor, a cover plate having notches at the edges thereof, means to hold the same centrally with respect to a can upon which it may be

placed, a bar pivotally mounted upon said cover plate for releasably securing the cover plate to the can, and a pivotally mounted punch adapted to be presented to each of the notches in the cover plate, substantially as described.

In testimony whereof I have hereunto set

my hand this 16th day of September A. D. 1912, in the presence of the two subscribed witnesses.

JEROME FOUNTAIN.
